UNITED STATES PATENT OFFICE

157,044

STOCKING

Richard L. Hall, Frederick, Md., assignor to Union Manufacturing Co., Frederick, Md., a corporation of Maryland

Application January 15, 1949, Serial No. 246

Term of patent 14 years

(Cl. D47—7)

To all whom it may concern:

Be it known that I, Richard L. Hall, a citizen of the United States, residing at 100 North Court Street, Frederick, in the county of Frederick and State of Maryland, have invented a new, original, and ornamental Design for a Stocking, of which the following is a specification, reference being had to the accompanying drawing, forming part thereof.

Fig. 1 is a side elevational view of a stocking with a welt top, showing my design; Fig. 2 is a fragmentary front view shown in perspective; Fig. 3 is a fragmentary side elevational view shown in perspective; Fig. 4 is a fragmentary side elevational view on an enlarged scale; Fig. 5 is an enlarged fragmentary view in perspective, looking at the welt top from the side; and Fig. 6 is a fragmentary view in perspective on an enlarged scale, looking at the welt top from the front, illustrating my design.

My design consists of a stocking having spaced triangular shaped blocks disposed in the welt top

thereof at substantially diametrically opposite sides of the welt top and spaced from an intermediate rectangular block disposed at the front of the welt top where the triangular blocks have their base portions extending adjacent the base portion of the rectangular block at the front of the welt and visible from the front of the stocking as shown.

I claim:

The ornamental design for a stocking, as shown and described.

RICHARD L. HALL.
